UNITED STATES PATENT OFFICE.

HOWARD THOMAS GAYTON, OF LOWER ARGYLE, NOVA SCOTIA, CANADA.

WINDLASS.

SPECIFICATION forming part of Letters Patent No. 337,571, dated March 9, 1886.

Application filed December 30, 1885. Serial No. 187,088. (No model.)

To all whom it may concern:

Be it known that I, HOWARD THOMAS GAYTON, a subject of the Queen of Great Britain, and a resident of Lower Argyle, in the county of Yarmouth, in the Province of Nova Scotia and Dominion of Canada, have invented certain new and useful Improvements in Windlasses; and I do hereby declare that the following is a full, clear, and exact description of the invention, which will enable others skilled in the art to which it appertains to make and use the same, reference being had to the accompanying drawings, which form a part of this specification, and in which—

15 Figure 1 is a front view of my improved windlass. Fig. 2 is a rear view of the same. Fig. 3 is a side view; and Fig. 4 is a perspective detail view of one of the pawl arms or boxes, showing portions of the same broken 20 away.

Similar letters of reference indicate corresponding parts in all the figures.

25 My invention has relation to windlasses, and more particularly to windlasses adapted to be used on board of vessels for lifting the anchor; and it consists in the improved construction and combination of parts of the same, as hereinafter more fully described and claimed.

In the accompanying drawings, the letters 30 A A indicate the two upright posts between which the drum B or barrel of the windlass is journaled, and C indicates the upright post which is placed forward of the windlass and upon which the operating mechanism is secured. The upper end of this post is formed with two perforated lips, D D, between which a lever, E, is pivoted at its middle upon a bolt, F, and the ends of this lever are socketed for the reception of two handles, G G, which have 35 their inner ends secured in the sockets by means of pins H. Two large cog-wheels, I I, are journaled upon the sides of the central upright upon short shafts projecting from the same, and the outer faces of these cog-wheels 40 have ratchet-wheels J J secured to their central outwardly-extending hubs, so as to leave spaces between the cog-wheels and the ratchet-wheels, and the faces of these ratchet-wheels are formed with outwardly-projecting flanges 45 K at the rims, the rims being wider than the bodies of the ratchet-wheels. Hollow boxes

or arms L have their inner open ends clamping the sides of the ratchet-wheels, and the edges of the sides of the boxes are cut out segmentally and formed with inwardly-projecting 55 flanges M, which fit inside of the projecting rims of the wheels and secure the boxes to the ratchet-wheels, while the wheels may revolve freely within the open flanged ends of the boxes. Pawls N, of which three are shown in 60 the drawings, although a greater or smaller number may be used, are pivoted with their inner ends upon bolts O, secured transversely in the boxes, and engage the forward rims of the ratchet-wheels, and the outer ends of the pawl 65 boxes or arms are provided with suitable eyes, P, to which are pivoted the lower ends of rods Q, pivoted at their upper ends to the ends of the lever. It will thus be seen that the ratchet-teeth upon the forward edges of the wheels 70 facing downward, and the pawls pointing upward and swinging upward, the said pawls will engage the ratchets and revolve the wheels when the outer ends of the boxes are raised, the boxes having their fulcrum upon the 75 circular flanges bearing against the annular rims of the ratchet-wheels, and the outer ends of the pawl-boxes are raised alternately by rocking the lever upon the top of the upright 80 by means of its handles. The cog-wheels connected to the ratchet-wheels engage small pinions R, secured upon the outer faces of large cog-wheels S S, journaled upon short shafts T, projecting from the upper end of the upright, and these cog-wheels in turn engage small pinions 85 U, journaled upon short shafts V V, projecting from the sides of the upright. These pinions engage cogged rims upon the drum of the windlass, the said rims W W being embedded in the surface of the drum, and it will be seen 90 that the sides of the annular grooves formed by thus embedding the cogged rims in the surface of the drum of the windlass will serve as guides for the pinions U, and cause them to engage squarely with the cogged rims W W. A 95 cogged rim, X, is secured upon the middle of the drum, and this rim is engaged by the notched or cogged lower end of a bolt, Y, sliding in vertical bearings Z upon the rear side of the upper end of the upright, and the said 100 bolt will be raised by the cogs of the rim when the windlass is revolved with its upper side

moving rearward, allowing the drum to be re-
volved in that direction, while it will engage the
cogs and prevent the drum from revolving
when the drum is revolved in the opposite
direction, which only can take place when
the bolt is raised out of engagement with the
cogged rim.

The pawl-boxes are preferably made in two
pieces, the side pieces of the boxes being
10 formed with flanges at their edges, which fit
upon each other, transverse bolts securing the
two halves together, the said construction en-
abling the boxes to be conveniently fitted upon
the ratchet-wheels and removed from the same.

15 It will be seen that on each movement of the
end of the reciprocating lever E its box L will
be raised, and, as previously described, par-
tially revolve its ratchet-wheel J, and the large
20 cog-wheel I, keyed on the same short shaft,
will also be partially revolved—that is, turn
for a portion of a revolution—and this partial
revolution of the large cog-wheel I will impart
an entire revolution or more to the small pin-
ion R, with which it meshes, and as the said
25 small pinion R is secured concentrically to the
side of the large cog-wheel S, the said large
cog-wheel S will also be revolved for an entire
revolution or more, and this large cog-wheel
S, meshing with the small pinion U on the
30 shaft V, will, on making one revolution, re-
volve the small pinion U three or more times,
and this small pinion U, engaging directly
with its cogged rim W on the drum of the
windlass, will turn the windlass with great
35 speed.

It will be seen from the foregoing that by

this peculiar construction and arrangement of
operative intermeshing parts each movement
of each end of the lever E will impart great
speed to the windlass, and thus enable a cable 40
to be wound up with great rapidity—a most
decided advantage in apparatus of this class.

Having thus described my invention, I claim
and desire to secure by Letters Patent of the
United States—

45 In a windlass, the combination of the drum
having cogged rims near its center, and hav-
ing also a central cogged rim, a pawl-bolt en-
gaging the central rim, the large cog-wheels
having ratchet-wheels secured to their faces 50
at a distance from the same, the small pinions
meshing with the said large cog-wheels and
rigidly secured to the sides of large cog-wheels,
and the small pinions intervening between the
said large cog-wheels and the cogged rims on 55
the drum of the windlass, pawl-boxes having
segmentally-cut-out inner ends formed with
flanges engaging the projecting rims of the
ratchet-wheel, and having pawls between their
sides engaging the teeth of the ratchet-wheels, 60
a lever having handles at its ends and pivoted
transversely above the cog-wheels, and con-
necting-rods pivoted to the ends of the lever
and to the outer ends of the pawl-boxes, as
and for the purpose shown and set forth. 65

In testimony that I claim the foregoing as
my own I have hereunto affixed my signature
in presence of two witnesses.

HOWARD THOMAS GAYTON.
